MACHINE FOR VOICING REEDS OF
HARMONICAS

Frank L. Johnson, Waterbury, Conn.

Application December 14, 1939, Serial No. 309,249

6 Claims. (Cl. 90—15)

This invention relates to a machine for voicing reeds of harmonicas and has for one of its objects the production of a simple and efficient machine whereby the reeds may be brought to very near accurate pitch or tone through the adjustment of the machine, thereby saving time in tuning the reeds.

A further object of this invention is the production of a simple and efficient means for automatically moving the reed plate or plates into and out of engagement with the cutters.

Another object of this invention is the production of an efficient tongue plate wherein the tongues are punched out in one plate at one stroke of the press and the tongue plate riveted to the base plate with two strokes of the press, by placing the tongues and plate in jig and piercing the rivets from the base plate and heading the rivets; the tongues afterwards being voiced by my improved machine.

In the drawings:

Figure 1 is a front elevational view of the machine, a portion of the reed plate being shown in longitudinal section;

Figure 2 is a side elevational view of the machine;

Figure 3 is a side elevational view of one of the cutting arms, a portion thereof being shown in section;

Figure 4 is a top plan view of a portion of the anvil block and reed plate; and

Figure 5 is a sectional view taken on line 5—5 of Figure 4.

By referring to the drawings, it will be seen that 10 designates the bed plate of the machine, which carries the standards 11. The standards 11 support the main shaft 12 within the bearings 13. Table supporting blocks 14 are carried by the bed plate 10 and these blocks are provided with V-shaped channels 15 within which the beveled side edges 16 of the sliding table 17 is mounted. A plurality of standards 18 are carried near the rear end of the bed plate 10 and carry a cam-supporting shaft 19 upon which the cams 20 and 21 are mounted.

A plurality of cutter arms 22 are carried by the shaft 12, as shown in Figures 1 and 2. An eccentric 23 is carried by the shaft 19 upon which eccentric is mounted a crank 24 which is pivotally connected at its forward end, as at 25, to the sliding table 17. This table 17 supports an anvil block 26 near its outer end and this anvil block 26 constitutes a support for the base plate 28, the tongues being supported upon the anvil 28a, as shown in detail in Figure 5.

Each cutter arm 22 carries a drive gear 29 which is keyed to the shaft 12 and this gear 29 meshes with an idle gear 30, the idle gear meshing with a gear 31 which carries the cutter 32. The cutter 32 projects slightly below the 5 lower edge 33 of the cutter arm 22 in each instance. Directly in front of the cutter 32 is arranged a port 34 into which fits a tube 35 which tube may be connected to a suitable source of air pressure for blowing chips and other accumulated matter from the reed plate upon which the cutters 32 carried by the arms 22 may be operating. An oil cup 36 is provided upon each arm 22 just above the gear 29, as shown in Figure 3. Through the medium of this oil cup 36, 15 the gears 29, 30 and 31 may be properly lubricated.

A roller 37 is carried by the rear end of each arm 22 and these rollers 37 engage the cams 21 carried by the shaft 19 for raising and lowering 20 the arms 22 which rock upon the shaft 12 as the rollers 37 pass over the surface of the cams 21. The roller 37 of each arm 22 is carried by a suitable block 38 which is adjustably mounted within the inner end of the arm 22, the block 38 25 being adjustable toward and away from the cam 21 by means of the screw 39, and the block being locked in position by means of the right-angularly extending screw 40. In this way, the roller 37 and its supporting block may be adjusted to a nicety, and may be held in this adjusted position. This adjustment of the roller 37 is provided to adjust the amount of cut and to take up for wear on the cutters. The gear 31 is preferably formed of bronze and the cutter 35 32 is preferably formed of steel, the gear being provided with a threaded extension which is threaded into the center of the cutter providing a central aperture having a suitable bearing, this being the conventional method employed. 40

As shown in Figure 2, the anvil block 26 may be mounted in the conventional manner upon the table 17 and provided with a suitable adjusting screw 28a for properly positioning the anvil 28a upon the table 17 with respect to the cutters 32.

The shaft 12 is driven by a motor or other means of power which in turn drives gear 41 by means of a worm 41a keyed to shaft 12. The shaft 42 carries a worm gear 43 which is keyed 50 to shaft 42 and is connected to one end of the coil spring 44, the opposite end of the coil spring being connected to the sleeve 45 which is slidably mounted upon the shaft 42. The spring 44 is so connected to the worm 43 as to permit the 55

worm to freely rotate independently of the spring 44. This sleeve 45 is connected to the upper end of a bell crank lever 46, which bell crank lever is pivoted, as at 47, on the bed plate 10. The opposite end of the bell crank lever 46 carries a roller 48 which travels over the face of the cam 20 and as this roller 48 falls within the recessed portion 49 of the cam 20, the spring 44 will throw the worm 43 or pull the worm 43 out 10 of engagement with the drive worm 50 carried by the shaft 19. A suitable means, such for instance, as one type of operating mechanism in the nature of a control link 51 may be connected to the lever 46 for manually actuating the same 15 to manually swing the lever 46 when desired. When the cam shaft 19 and the cam 20 make one complete revolution, the roller 48 on the lever 46 falls into the recessed or depressed portion 49 causing the shaft 19 to discontinue its 20 rotation, thereby stopping the table 17 in its forward position to permit the operator to remove the reed plate 28 and place the next one in position upon the anvil block. The cam 20, however, keeps the cam shaft, gear and worm 25 engaged while the cam shaft makes a revolution, or until the roller 48 falls into the recessed portion 49 of this cam.

From the foregoing description, it will be seen that the table 17 has a reciprocating movement 30 and moves forward and backwardly upon the standards 14, and this operation is occasioned through the medium of the crank 24 and the eccentric 23 which is carried by the shaft 19. The main drive shaft 12 which supports the cutter 35 arms 22 also drives the shaft 42 through the medium of the worm drive 41. This in turn imparts rotary movement to the shaft 19 through the controlled position of the worm 43 when the worm is moved into and out of engagement with 40 the worm 50. Through the medium of the cam 20, the operation of the device will be automatically stopped, this worm 43 constituting an automatic clutch mechanism for discontinuing the operation of the cutters 32 at predetermined intervals, whereby the work may be removed or replaced, the cutter arms 22 being at proper intervals raised and lowered into cutting positions when the work is brought at timed intervals into cutting positions with respect to the cutters 32. 45

50 As shown in Figures 1 and 2, the shaft 42 is hung upon a yoke 52 which is carried by the shaft 12 and is preferably located to one side of the cutter arms 22, as shown in Figure 1.

In carrying out my invention, I preferably 55 punch the tongues 27 which constitute the reeds out in one plate 27^a at one stroke of the press and then rivet this tongue-carrying plate to the supporting base plate 28 by placing the tongues and plate in jig and piercing the rivets from the 60 plate and heading the rivets. The tongues then are fed to the cutters 32 after being placed upon the anvil block 26, the eccentric 23 moving the tongue-carrying plate under the cutters for voicing the tongues. The sliding table provides this 65 movement through the operation of the eccentric 23 and the crank 24. The cams 21 raise the back ends of the cutter arms 22 to bring the cutters 32 into contact with the tongues when the table is in the correct position.

70 It should be understood that certain detail changes in the mechanical construction, combinations and arrangements of parts may be employed without departing from the spirit of the invention, so long as such changes fall within the 75 scope of the appended claims.

Having described the invention, what is claimed is:

1. A mechanism of the class described comprising a base, a work-supporting table reciprocably mounted upon the base, a main drive shaft 5 supported above said table, cutter arms rockably mounted upon the main drive shaft, cutters carried by the cutter arms and adapted to be brought into and out of engagement with the work as the arms are rocked, a second shaft carried by the base, means carried by the second shaft for reciprocating the table in timed relation whereby the work carried by the table will be brought directly under the cutters of the cutting arm as the cutters are moved toward the work, means for 15 driving the second shaft from the drive shaft, said last mentioned means comprising a third shaft having a worm drive connection with the second shaft, an operating lever for rendering the worm drive inactive, and a cam carried by the 20 second shaft engageable by the lever for controlling the operation of said worm drive means.

2. A mechanism of the class described comprising a base, a work-supporting table reciprocably mounted upon the base, a main drive shaft 25 supported above said table, cutter arms rockably mounted upon the main drive shaft, cutters carried by the cutter arms and adapted to be brought into and out of engagement with the work as the arms are rocked, a second shaft carried by the 30 base, means carried by the second shaft for reciprocating the table in timed relation whereby the work carried by the table will be brought directly under the cutters of the cutting arm as the cutters are moved toward the work, means for 35 driving the second shaft from the drive shaft, said last mentioned means comprising a third shaft having a worm drive connection with the second shaft, an operating lever for rendering the worm drive inactive, a cam carried by the second shaft 40 engageable by the lever for controlling the operation of said worm drive means, and a coil spring interposed between the lever and the worm driving means.

3. A mechanism of the class described comprising a base, a work-supporting table reciprocably mounted upon the base, a main drive shaft supported above said table, cutter arms rockably mounted upon the main drive shaft, cutters carried by the cutter arms and adapted to be brought 50 into and out of engagement with the work as the arms are rocked, a second shaft carried by the base, means carried by the second shaft for reciprocating the table in timed relation whereby the work carried by the table will be brought directly under the cutters of the cutting arm as the cutters are moved toward the work, means for 55 driving the second shaft from the drive shaft, said last mentioned means comprising a third shaft having a worm drive connection with the second shaft, an operating lever for rendering the worm drive inactive, a cam carried by the second shaft 60 engageable by the lever for controlling the operation of said worm drive means, a coil spring interposed between the lever and the worm driving means, and means for manually operating said lever.

4. A machine of the class described comprising a base, a work-supporting table reciprocably mounted upon the base, a main drive shaft supported above the table, cutter arms rockably mounted upon the main drive shaft, a second shaft carried by the base, cam means carried by the second shaft for rocking the cutting arms, and eccentric means carried by the second shaft 70 75

for reciprocating the table and moving work carried by the table into an operative position for engagement with the cutting arms.

5. A machine of the class described comprising a base, a work-supporting table reciprocably mounted upon the base, a main drive shaft supported above the table, cutter arms rockably mounted upon the main drive shaft, a second shaft carried by the base, cam means carried by the second shaft for rocking the cutting arms, eccentric means carried by the second shaft for reciprocating the table and moving work carried by the table into an operative position for engagement with the cutting arms, and cutting means carried by the cutting arms and driven from said drive shaft.

6. A machine of the class described comprising a base, a work-supporting table reciprocably mounted upon the base, a main drive shaft supported above the table, cutter arms rockably mounted upon the main drive shaft, a second shaft carried by the base, cam means carried by the second shaft for rocking the cutting arms, eccentric means carried by the second shaft for reciprocating the table and moving work carried by the table into an operative position for engagement with the cutting arms, a roller carried by the cutter arms for engaging said cam means, and means for adjustably holding said roller upon said rocker arm. 5 10
